SWEATER RE-FORMING APPARATUS
August F. Paris, 1025 Oak St., Brockway, Pa.
Filed Sept. 4, 1962, Ser. No. 221,233
20 Claims. (Cl. 223—70)

This application is a continuation-in-part of applicant's copending application, Serial No. 146,042, filed Oct. 18, 1961, entitled "Sweater Sizing and Shaping Machine," now abandoned.

This invention generally relates to procedure and apparatus for sizing and shaping garments. This invention relates more specifically to apparatus and procedure for stretching and re-forming knitted garments, such as sweaters, that have been shrunk as the result of dyeing, washing or other manufacturing treatments.

Many types of sweaters are knitted with undyed yarn into their desired final form and are then dyed to the desired color as an entire unit. The dyeing operation often shrinks the sweaters out of size and deforms their shape and styling. Such malformed sweaters must be re-formed into their desired size and styling to be satisfactory for sale.

In addition to shrink-causing dyeing operations, sweaters are often soiled during manufacture and must be washed prior to finishing. Also, unevenly knitted sweaters are treated with chemical sizing compounds that enable them to hold their proper shape. These and other treatments will cause sweaters, and knitted garments in general, to shrink and require re-forming.

Sweaters, whether malformed or not, require a finishing operation, such as pressing, to remove wrinkles developed during manufacturing processes. Also finishing operations will slightly re-form sweaters to remove small imperfections and unitize or give body to the garment. One preferred means of finishing sweaters involves the use of a pre-shaped, expanding-frame that fits inside an individual sweater. A sweater fitted onto such a frame will be placed under slight wrinkle-freeing tension. By subjecting a sweater under such tension, first to steam and then to dry air, the sweater will be "pressed" or finished in its final desired configuration without disturbing the natural texture or surface character of the yarn. Although an expanding-frame garment finisher will stretch a knitted garment slightly, it cannot satisfactorily re-form a sweater that has seriously shrunk as the result of chemical treatment.

I have considered the problems existing in the garment finishing art summarized above, and have found that these problems have not been met with a completely satisfactory solution.

According, an object of my invention has been to discover and develop a procedure for uniformly re-sizing and re-shaping malformed garments such as sweaters;

Another object of my invention has been to produce a machine that can be conveniently operated to automatically stretch and re-form sweaters;

Another important object of my invention has been to provide a single machine on which a sweater can be loaded for both wrinkle-free finishing and stretch re-sizing and re-shaping;

A further object of my invention has been to provide a sweater re-forming machine that can be easily adapted for use with sweaters of various sizes and shapes, and that can be pre-set for automatic operation on sweaters of the same size and shape;

A further important object of my invention has been to provide a sweater re-forming machine that is composed of relatively simple, easy-to-operate and maintain mechanisms;

2

These and other important objects of my invention will appear to those skilled in the art upon reading and understanding the following description of my invention wherein specific reference may be had to the accompanying drawings of which:

FIGURE 1 is a perspective view of the sweater finishing machine constituting my invention which is broken away in part to show certain internal details of the machine;

FIGURE 2 is a top view of my machine partly in cross section taken along line II—II of FIGURE 1;

FIGURE 3 is a fragmental perspective view of a portion of my machine as set up to finish properly formed sweaters;

FIGURE 4 is a perspective rear view of a baffle plate that can be used with my machine for finishing either properly formed or malformed sweaters;

FIGURE 5 is a fragmental perspective view of a portion of my machine as set up to finish malformed sweaters;

FIGURE 6 is a fragmental side view in cross section of the main sweater gripping means employed in finishing malformed sweaters;

FIGURE 7 is a schematic layout of a control system for operating the stretching mechanism of my machine;

FIGURE 8 is a fragmental perspective view of a collar forming attachment employed in conjunction with my machine; and

FIGURES 9 and 10 are fragmental front views of a portion of my machine illustrating alternative arrangements for attaching the collar finishing attachment of FIGURE 8 to my machine.

One phase of my invention relates to the use of a garment finishing stand or form having the desired side and arm contours for shaping the garment. Upper portions of the garment are supported on the finishing stand while the garment is stretched by means that grip its bottom periphery or waist portion. Another phase of my invention relates to the use of pre-set adjustable stretching limits and adjustable-length pneumatic-actuator piston rods whereby the re-forming machine can be pre-set to automatically reproduce a desired stretching operation for garments of different size.

Another important phase of my invention relates to the use of sweater gripping means that are selectively automatically held in either a gripping or non-gripping position to make the most efficient use of the machine operator's hands.

A further phase of my invention relates to the use of a collar forming attachment that can be selectively employed to stretch and re-form the collar and upper portions of the sweater or to hold the collar and upper portions of the sweater in a pre-formed position during the stretching operation, or to move and stretch the collar and upper portions of the sweater somewhat less than the stretching movement applied to the garment waist portion.

Referring now more specifically to the drawings, in FIGURE 1 there is shown a garment finishing machine 10 including a base or support part 11 that is mounted on the shop floor, and a central column or frame post structure 12 that is mounted on the supporting base and extends vertically upwardly through the machine. The central column 12 consists of a hollow rectangular tube-like member (see FIGURES 1-3) that has perforations or open portions 14 throughout its length to permit the escape of steam and air from its interior to the garment being finished. Steam conduits 15 and air conduits 16 are provided with discharge orifices spaced along their length to supply steam and air (from sources not shown) to the interior of the garment being processed, as required.

A stand, form, or expanding finishing frame 20 is mounted on an upper portion of the central column 12 for receiving and supporting the garment being finished (not shown). The finishing frame 20 is provided with identical halves which each include a shoulder member or frame part 21 that is pivotally connected to an upper end portion of the central column 12 and extends outwardly therefrom. An upper arm member or frame part 22 is slidably connected to the shoulder member 21 by means of a pin and slot connection 23. A lower arm member or frame part 24 is slidably and pivotally connected at one end to the outer end of the upper arm member 22 by means of a pin and slot connection 25. A side-creaser bar or edge shaping linkage 26 is pivotally connected at its upper end to a side adjuster link or expander member 27 by a removable pin or bolt 28.

The side-creaser bar 26 is laterally-adjustably supported at its lower end by a perforated sizing link or brace 29 that is securely connected to the base 11 and extends outwardly therefrom. The inner end of the lower arm portion is also pivotally connected to the side-adjuster link 27 by the pin 28.

The side-adjuster link 27 (see FIGURE 1) is connected to the central column 12 for rotative outer and inward expanding movement by a pivotal connection 30 adjacent its lower end portion. A pneumatic cylinder frame-expanding jack, actuator or other motor means 31 is supported within the central column 12 and is operatively connected to both of the side-adjuster links 27 through a pair of toggle links 32. It will be seen that as the pneumatic actuator 31 causes the toggle links 32 to pivot the side adjuster links 27 outwardly, the side-creaser bars 26 and the arm-forming frame members 22 and 24 will spread or expand. Conveniently, the actuator can be provided with an adjustable stroke limit stop (not shown) that will automatically determine the ultimate degree of frame expansion as required for garments of a given size and material. The pin and slot sliding connections 23 and 25 between the arm and shoulder members 21, 22, and 24, permit the arm-receiving parts of the finishing frame 20 to be collapsed and rotated upwardly to facilitate loading of a sweater onto the machine.

If the machine is to be used for finishing properly formed garments, a pair of baffle plates, counterplates or waist holders 40 (see FIGURES 3 and 4) having a limited number of spaced perforations or open portions 41 therethrough are mounted directly on the central column 12 of the machine. The plates 40 are also provided with two strips 42 of friction material such as traction cloth, that frictionally hold a portion of a garment in place during processing.

The plates 40 are removably secured to the central column 12 by a track or flange 43 that engages a rail portion 12a of the central column 12, and a spring clip or other resilient means 44 that engages an opposed wall 12b of the central column 12 (see FIGURE 4). The plates 40 may conveniently be vertically repositioned to engage a peripheral waist portion of the garment being finished. The plates 40 so positioned protect the resilient tight-fitting waist ribbing of the garment from the softening action of the steam. As the machine 10 is to be used for finishing garments of all sizes and shapes, several different size plates 40 may be selectively employed.

The mechanism for stretch-re-forming malformed garments is shown generally in FIGURES 1 and 2 and includes vertically movable means, such as an elevator or vertically movable open frame 50 as its primary component. The elevator is constructed of forward and rearward side bars or frame parts 50a and 50b. A pair of vertical guide plates or counterplate support means 51 (see especially FIGURES 2 and 5) are securely mounted on central internal portions of the elevator 50. Each guide plate 51 has a pair of horizontally-spaced, vertically-extending tubes or guide portions 52 securely connected to their inwardly facing surfaces (see FIGURES

5 and 6). Two pair of vertical, elevator-guide rails or rods 53 are mounted by upper and lower brackets 55 onto the front and rear portions of the central column 12. The tubes 52 slide vertically on the rods 53 to permit smooth vertical movement of the elevator 50 while maintaining the elevator 50 perfectly horizontal.

The elevator 50 supports a pair of forward and rear clamping means 60 that grip and protect the lower peripheral portions of the garment being stretched. Each clamping means 60 includes a counterplate or waist holder 40 that may be the same member employed for finishing well-formed garments as discussed in connection with FIGURES 3 and 4. Each plate 40 is removably connected to an associated vertical plate 51 as by a pair of resilient clips 45 (see FIGURE 5). Each counterplate 40 is also supportingly connected to the elevator 50 by a pair of horizontally spaced strips or resilient support members 54 of spring-like material. The strips 54 are connected at their upper ends to side portions of the counterplate 40 and at their lower ends to internal surfaces of the elevator 50. The strips 54, together with the resilient clips 45 that connect the guide plates 51 and the counterplates 40, permit the counterplates 40 to have a degree of horizontal flex or resilient horizontal displacement.

Each counterplate 40 includes a central or interior portion 40a that is flat, and constitutes the major horizontal extent of the plate. Each counterplate 40 also has a pair of inwardly inclined edge or end portions 40b that are integrally formed with the central portion 40a and provide a body-like contour for sweater-forming purposes. The central and end portions 40a and 40b provide an outwardly facing convex gripping surface to which is attached strips of friction material 42 such as commercially available traction cloth. The vertically central portion of the counterplate is perforated with a series of spaced open portions 41 that permit a controlled limited passage of steam and air through the waist region of the garment being finished. Conveniently, as mentioned above, the counterplate 40 used for stretch-re-forming are also used as a baffle plate for protecting the ribbing of well-formed garments as shown in FIGURES 3 and 4.

A perforated, vertically extending baffle or protector plate 56 (see FIGURE 5) is mounted on each counterplate 40. The baffle 56 extends upwardly along the interior of sweaters being stretched to protect the sweaters from snagging on internal parts of the machine 10, such as extra baffle plates 40 that may be connected to upper portions of the central column 12 by their clip and rail connections 43 and 44.

A pair of pivot brackets or flanged blocks 57 (see FIGURES 1, 2, and 6) are welded or otherwise securely mounted on an outer central surface of the elevator 50. Each bracket 57 has a pair of spaced pins or bolts 57a that pivotally support an actuating link 58. A clamping plate or outer gripping member 59 is operatively connected to the link 58 by a pin, bolt, or other suitable connecting member 61. The clamping plate 59 cooperates with an associated counterplate 40 to clamp-grip and protect a major part of the garment waist portion. As is best shown in FIGURE 6, the clamping plate 59 has traction plate 62 mounted on its inwardly facing surface. The traction plate 62 is preferably constructed from thin perforated aluminum grid material that is bent or boxed to present an inwardly-offset, vertically-centrally located gripping part 62a. The inwardly facing surface of the traction plate 62 is roughened to frictionally hold the clamped portion of a garment being processed. By constructing the traction plate 62 of perforated offset material, an exhaust is provided to permit the flow of a limited controlled amount of steam and drying air through the gripped waist portion of the garment, from the central perforations 41 of the counterplate. As is best shown in FIGURE 6, an overcenter

spring, snap or clamp positioning means 63 is connected to the pivot bracket 57 and the supporting link 58 at locations such that its resilient force will selectively pull its associated clamping plate 59 to a non-clamping open position as shown in the forward portion of FIGURE 1 and the full line view of FIGURE 6, or into a closed clamping position as shown in the rearward portion of FIGURE 1 and the broken line view of FIGURE 6. The pivot link 58 is provided with a cross bar handle or gripping means 64 that facilitate manual movement of the clamping plates 59 into a desired one of their selective positions.

A pair of side-edge grippers or clamping members 70 are provided for engaging the outer side edge surfaces of a sweater being processed. The side-edge grippers 70 cooperate with the side-creaser bars 26 to grip the side edge parts of the sweater waist portion. The side-edge grippers 70 each include an inwardly-open, U-shaped clamping flange 71 that is resiliently supported by a leaf-spring or thin metal arm 72. The arm 72 is carried by an H-shaped block, carriage or sliding support member 73. The side bars 50a and 50b of the elevator 50 provide a supporting track or table along which the block 73 can move and carry the clamping flange 71 into and out of operative clamping engagement with the side-creaser bars 26.

A pair of guide rods or bars 74 that are slidably positioned in elongated bearing portions 50c of the elevator 50 (see the right-hand portion of FIGURE 1) and are each securely connected to a respective block 73 to guide the block and its associate clamping flange 71 in their horizontal movement. The outer end of each rod 74 is provided with a handle or knob 75 which may be grasped and pulled outwardly by the machine operator to disengage its associated U-shaped clamping flange 71 from its cooperative relationship with the side-creaser bars 26. I prefer to also provide each block 73 with a finger tab or flange 76 that extends outwardly toward the machine operator. The finger tabs 76 provide convenient alternative means for moving the blocks 73 outwardly from their clamping position.

In order to make the most efficient use of the machine operator's hands, there is provided a pair of ratchets, latches, or spring-loaded hook assemblies 77 that are located adjacent the outer or non-clamping positions of the side-edge grippers 70. Each ratchet 77 includes a pivotally mounted, downwardly extending hook portion 78 that has an inwardly facing tapered edge 78a. The hook portion 78 is biased downwardly by suitable resilient means such as a coil spring (not shown). Each block 73 has a lip or tooth portion 73a that is provided by a thin metal strip securely attached to the outwardly facing surface of the block. As the block 73 is moved outwardly by the handle 75 on the rod 74, the tooth portion 73a engages the tapered edge 78a of the downwardly extending hook 78, lifts the hook, and moves into a secure hook engagement whereby the block 73 is held in an outer non-clamping position.

Each block 73 is also provided with a spring or other resilient means 79 for urging the block towards its central operative position wherein the U-shaped clamping bracket 71 co-operates with the side-creaser bars 26. Outward manual movement of the blocks 73 is thus opposed by the resilient force of the springs 79. Each ratchet 77 is provided with a key or finger gripping portion 77a that extends outwardly toward the machine operator. The construction of the ratchet 77 is such that depression of the key 77a will lift the hook portion 78 and release the lip portion 73a of the block 73 to allow the block to slide inwardly under the resilient force of the spring 79. It will thus be seen that the machine operator can form and shape a waist and side portion of the garment about the side-creaser bars 26 as desired and while holding the thus formed garment portion in position, depress the key 77a with his other hand to re-

lease the block 73 and permit the spring 79 to bring the U-shaped clamping member 71 into cooperation relationship with the side-creaser bar 26.

The machine 10 is to be used on a production line basis and accordingly it is desirable that it be capable of accurately reproducing any given stretch-re-forming operation. A pair of stroke limit members 80 are provided to enable the machine operator to pre-set the degree of stretch, the final garment length, or both. The stroke limit members each include rearward and forward vertical bars or pin racks 81 and 82 between which end portions of the elevator 50 are positioned, as shown in FIGURES 1 and 2. The bars 81 and 82 extend vertically upward from a base supported flange 83 on which they are mounted, throughout the entire range of potential elevator positions. The bars 81 and 82 of each stroke limit member 80 are joined at their uppermost end by an upper cross piece 84 and at an intermediate location and adjacent the lowermost elevator position by a lower cross piece 85. These cross pieces enhance the stability of the stroke limit members 80 and provide ultimate limits for the movement of the elevator 50.

The stroke limit members 80 are adapted to carry adjustable stop or limit means such as removable limit pins 86 (see FIGURES 1 and 2). The pins 86 each include a gripping or handle portion 86a that is formed integrally with a tapered shank portion 86b. The rearward and forward bars 81 and 82 of the stroke limit members 80 have several pairs of aligned open portions or pin-receiving means 87 spaced at convenient intervals therealong throughout the potential range of elevator movement. The open portions in the forward bar 82 are slightly larger than the open portions in the rearward bar 81, so that a pair of such aligned open portions 87 will tightly receive the tapered shank 86b of the limit pins 86. Two limit pins 86 are employed on each stroke limit member 80; one to determine the starting level of the elevator 50, and another to determine the end of the stretching stroke or final garment length.

A pair of pneumatic cylinders, jacks or other linear motor devices 90 constitute a power source for moving the elevator 50 along the rails 53. The jacks 90 each include a power output link or piston rod 91 that extends upwardly out of the cylinder and is operatively connected to the elevator 50 through a piston rod, adjustable length extension, or connecting linkage 92. The extension 92 is constructed of a pair of substantially parallel, spaced, vertical bars 92a that are connected at their end by upper and lower cross blocks 92b and 92c, respectively. The lower cross block 92c is secured, as by a threaded connection, to the upper end of an associated piston rod 91. The bars of the piston rod extension 92 have a plurality of spaced open portions 92d extending therethrough for receiving pins, bolts, or other elevator-connecting means. The end portions of the elevator 50 are connected to the jacks 90 by a lower bolt, pin or elevator-connecting means 93 that passes through the bars 92a just below the elevator 50. The lower bolt 93 supports the elevator during its initial or non-stretched position. An upper bolt 94 passes through the bars 92a just above the elevator 50 to operatively engage the elevator when the piston rods 51 move downwardly on the garment stretching stroke. The machine 10 is intended to accommodate garments of various size and, accordingly, a plurality of spaced open portions 92d are provided in the extensions 92 to selectively receive the upper and lower bolts 94 and 93. The spacing of portions 92d is such that a convenient variety of elevator connecting locations is available.

The extensions 92 permit the jacks 90 to operate through their entire range if necessary, regardless of the size of garment being processed. To obtain a maximum range of operation from the jacks 90, it is only necessary to position the lower bolt 93 to hold the elevator 50 against the

upper stroke limit pin 86 when the piston rod 91 is in its upper position.

Air pipes or conduits 95 are connected to opposite ends of each of the jacks 90. A valving arrangement for controlling the operation of the jack is shown schematically in FIGURE 7. A distributor or spool valve 96 is mounted within a casing 97 to selectively connect either upper or lower end portions of the jacks 90 with a high pressure air source 98 while simultaneously connecting other ends of the jacks with a low pressure or drain source such as the atmosphere. In the position shown the distributor valve 96 is connecting the high pressure source 98 to the lower portion of the jacks 90, thus causing the jacks to hold the elevator 50 (see FIGURE 1) in its uppermost or starting position.

An actuator rod 99 is operatively connected to the distributor valve 96 and extends through a coil or solenoid 100 by which the valve 96 can be positioned as desired. A biasing means such as compression spring 101 urges the actuator rod 99 and the valve 96 to the position shown. The solenoid 100 is the output of a control circuit that is powered by a battery or other source of electrical current 102 and is controlled by a switch 103. Preferably, the control switch 103 is interrelated with the control of the steam and air supply with the control of frame-expanding jack 31 to cause sequential or simultaneous operation thereof. When the operator closes the switch 103, the solenoid 100 will be energized to pull the distributor valve 96 to the right of FIGURE 7 and connect the upper portion of the jacks 90 with a source of high pressure air while simultaneously connecting the lower portion of the jacks with the atmosphere. The pressure air thus supplied will cause the piston rods 71 to move downwardly to lower the elevator 50 and stretch a garment loaded on the machine 10. When the control circuit is broken by release of the switch 103, the compression spring 101 will return the valve 96 to its normal position whereby the source of pressure air 98 is connected to the bottom of the jacks 90. The jacks 90 will thereby return the elevator 50 to its upper or starting position.

Referring again to FIGURE 1, there is shown a collar and front forming attachment 110 that is securely mounted on the forward counterplate 40 for vertical movement therewith. FIGURE 8 shows an enlarged fragmental section of the collar-forming attachment 110 to illustrate its construction. A backing plate or strip 111 extends vertically for the length of the attachment 110 and has suitable open portions or bores 112 adjacent its ends for receiving connecting means as hereinafter discussed (see FIGURES 1, 9, and 10). A plurality of raised members 113 having slotted portions 114 therein are mounted on by rivets or spot welds 115 to the outer surface of the strip 111. The slotted portions 114 in the raised members 113 open at their side edges to receive collar-forming or molding pins 116 as shown in FIGURE 8 whereby a sharp point is exposed for use in molding the sweater. It will thus be seen that pins 116 can be located as necessary along the front of the machine to aid in molding and holding local portions of the sweater being processed as required.

FIGURES 9 and 10 show alternative arrangements for mounting the collar-forming attachment 110 on the machine 10. In FIGURE 9 the collar attachment 110 is shown securely mounted on the center column 12 where it is held in a fixed position during the stretching operation. Of course, the collar attachment is not connected to the counterplate 40 when the mounting arrangement of FIGURE 9 is employed. FIGURE 10 shows an arrangement wherein the collar-forming attachment 110 is resiliently connected by upper and lower springs 117 and 118 at its respective ends to the stationary center column 12 and to the moving counterplate 40. When this arrangement is employed, vertical movement of the counterplate 40 will cause a lesser movement of the collar-forming attachment 110. The actual movement of the collar

attachment 110 will be determined by the relationship between the spring contacts of the upper and lower springs 117 and 118.

Thus it will be seen that a variety of sweater reforming motions and stretching movements can be obtained by my machine as required to meet the variety of fashionable sweater types such as V-necks, cardigans, turtle necks, etc. The variety of movements also will enable the machine to correct many different types of sweater irregularities.

The machine 10 is conveniently adapted to finish sweaters having ribbed or other type cuffs that may require special attention. For this purpose a pair of outwardly diverging vertical clamp-holding rods 120 are supported by the base supported flange 83. Each of the rods carries an adjustably positioned clamping member 121 for holding the cuff portion of a garment being processed. The clamping member 121 shown in FIGURE 1 consists of a pair of mutually pivoted, resiliently-spring-biased clamping halves 122 which each include a cuff-engaging clamp jaw 123, a rod-holding cylindrical portion 124, a hinged portion 125, and a gripping portion 126. The hinged portions 125 of the two clamping halves interfit and are joined by a suitable pin to form a unitary clamp. When a garment having a cuff that requires special attention is loaded onto the machine, the rods 120 are individually flexed inwardly and the gripping portions 126 of the clamping member 121 are squeezed to open the jaws 123 and also allow the clamp to be adjusted along the rod 120. When the clamp 121 is in place, it is engaged with the cuff and the rod 120 is allowed to spring outwardly applying a slight tension to the sleeve.

The operation of my invention as thus described is as follows: The arm-receiving portions 21, 22, 24 of the garment frame 20 are collapsed as shown in the left-hand portion of FIGURE 1. The garment is loaded onto the frame 20 and the arm portions are extended to hold the garment in place as shown in the right-hand portion of FIGURE 1. The garment is pre-steamed to make it pliable and easy to manipulate on the frame. If the garment has cuffs requiring special attention, the clamps 121 are attached as described above and the sleeves are placed under a slight tension. If the garment requires stretching due to deformities caused by dyeing or other manufacturing treatment, the waist portion is fitted into the various gripping means 40, 59, and 70 of the elevator. The operator will attach the gripping members one at a time by first hand-forming and locating a section of the garment waist portion on a corresponding side-creaser bar 26 and while holding the garment in place, will depress the key 77a to release the side-edge clamping member 71. When both side edges are secured in place, the front of the garment is molded and located on the counterplate 40, using pins if necessary for the central portion; the clamping plate 57 is then brought into cooperative engagement with the front portion of the garment. This operation is repeated for the back portion of the garment. When the garment is in place on the machine, the frame expander jack 31 and the stretching jacks 90 are energized to respectively expand the frame and remove the wrinkles from the garment, and lower the elevator 50, thus stretching the garment and restoring it to its desired shape and styling. During the stretching operation, the garment is subjected to first a charge of steam from conduit 15 which softens the fibers and makes them pliable, and then is automatically subjected to a charge of drying air from conduit 16, that sets or fixes the fabric in its newly formed configuration.

It will thus be seen that I have provided a single machine that will perform the ordinary operation of wrinkle-free finishing knitted garments such as sweaters, and will also correct irregularities in the garments caused by manufacturing processes. My machine can be set to accurately and automatically reproduce a given re-forming and finishing operation for garments of a given size and shape. Furthermore, my machine can easily be adapted

by the interchange of easily removable parts, to finish and completely re-form garments of widely varied sizes and shapes.

Having thus described my invention and an illustrative embodiment thereof, I claim:

1. In a sweater finishing machine having a frame constructed on a vertical axis and including portions for forming the arms, shoulders, and body parts of a sweater, a stretching mechanism comprising: means for gripping lower edges of a sweater to be stretched, means operatively connected to said gripping means for moving said gripping means uniformly along said vertical axis away from said shoulder forming frame portion, and means for subjecting the sweater to sequential charges of steam and drying air while the sweater is being simultaneously stretched by said moving means.

2. In a sweater finishing machine having a base, a central column securely connected to the base and extending vertically upward therefrom, a frame for forming arm and body portions of a sweater to be finished operatively connected to the central column, means for expanding and contracting the frame to apply a finishing tension to a sweater being processed, and means for subjecting the sweater being processed to charges of steam and drying air, a stretching mechanism comprising: means for gripping lower edges of a sweater to be processed, an elevator for supporting said gripping means, track means mounted on the central column for guidingly supporting said elevator for vertical sliding movement with respect to the central column, and power means for moving said elevator vertically downwardly.

3. In a sweater finishing machine as defined in claim 2, said stretching mechanism further comprising: adjustable means for limiting the downward travel of said elevator.

4. In a sweater finishing machine as defined in claim 2, said stretching mechanism further comprising: adjustable limit means for providing a variable range of elevator movement.

5. In a sweater finishing machine as defined in claim 2, said stretching mechanism further comprising: means for holding localized portions of the sweater being processed in a pre-formed configuration during downward movement of said elevator.

6. In a sweater finishing machine as defined in claim 2, said stretching mechanism further comprising: additional means for gripping localized portions of the sweater being processed, first resilient means operatively connected between said additional gripping means and the center column, and second resilient means operatively connected between said additional gripping means and said elevator, whereby downward movement of said elevator will cause a lesser downward movement of said additional gripping means.

7. In a sweater finishing machine as defined in claim 2, said stretching mechanism further comprising: additional gripping means operatively connected to said elevator for gripping localized portions of the sweater being processed and moving the portions thus gripped downwardly with movement of said elevator.

8. In a sweater finishing machine having a base, a vertical center column extending upwardly from the base, a pair of frame parts for receiving arms of a sweater to be finished, a pair of side-creaser bars that are operatively connected to said frame parts, and means for expanding said frame parts and side-creaser bars, a stretching mechanism comprising: an elevator surrounding an intermediate portion of the central column, means for moving said elevator vertically along the central column, means mounted on said elevator for gripping substantially all of the lower edge portion of a sweater to be stretched.

9. Apparatus as defined in claim 8, said gripping means of said stretching mechanism including U-shaped side-edge holders that cooperate with the side-creaser bars to grip side edge portions of the sweater.

10. Apparatus as defined in claim 8 wherein said gripping means further comprises a pair of U-shaped side-edge holders that cooperate with the side-creaser bars to grip the side edges of the sweater, each of said U-shaped side-edge holders being resiliently supported by a carriage block that is mounted for horizontal sliding movement on said elevator, and means for resiliently urging each of said blocks and their associated U-shaped side-edge holders toward their operative clamping positions.

11. Apparatus as defined in claim 10 wherein ratchet means are provided for selectively holding each of said blocks in an unclamped position.

12. Apparatus as defined in claim 8, wherein said gripping means includes a pair of counterplates supported on said elevator, a pair of clamp plates pivotally supported on said elevator in an opposed cooperative relationship with said counterplates, and a pair of U-shaped side-edge holders for cooperating with the side-creaser bars to grip side edges of the sweater.

13. Apparatus as defined in claim 12, wherein over-center snap means is provided for each clamp plate to urge the clamp plate to one of two selective positions.

14. Apparatus for finishing a sweater or the like comprising a base, a vertical center column having a hollow interior mounted on said base and extending upwardly therefrom, means for selectively supplying steam and air to the interior of said center column, a plurality of open portions in said center column for passing steam and air therethrough, an expanding frame having a pair of collapsible and expandable arm-receiving portions operatively connected to an upper portion of said vertical center column, actuator means for expanding and contracting said arm-receiving portions, a pair of side-creaser bars extending vertically on opposed sides of said center column and operatively connected to said actuator means for receiving side-edge portions of the sweater, an elongated open elevator surrounding said center column and said-creaser bars, a plurality of rails mounted on said base and extending vertically along said center column, a plurality of tracks securely connected to said elevator for operatively receiving said plurality of rails, a pair of opposed side-edge grippers slidably mounted on said elevator for movement toward and away from said center column, said side-edge grippers each including a U-shaped clamping flange for cooperating with a respective side-creaser bar to clamp-grip side edge portions of a sweater, resilient means for urging said side-edge grippers toward their operative clamp-gripping position, releasable latch means for selectively retaining said side-edge grippers in a non-clamping position, forward and rearward counterplates operatively connected to said elevator for vertical movement therewith, each of said counterplates having outwardly facing convex surfaces for engaging interior waist portions of the sweater, a pair of clamp plates pivotally connected to said elevator in opposed cooperative relationships with respect to said counterplates, each of said clamp plates having an inwardly-facing concave surface for engaging exterior waist portions of the sweater and together with its associated counterplate, clamp-grip

54

17. Apparatus as defined in claim 14 wherein, at least one protective baffle is mounted on, and extends upwardly from, one of said counterplates, to protect adjacent portions of the sweater.

18. Apparatus as defined in claim 14, further comprising a pair of resilient bars that are operatively supported by said base and extend upwardly to adjacent said arm-receiving portions, and clamp means adjustably secured to each of said bars for clamp-engaging cuff portions of the sweater.

19. A method of shaping a sweater comprising:

(A) internally supporting arm and shoulder portions of the sweater on a frame that provides substantially the desired sweater size and shape,

(B) gripping substantially the entire waist portion of 15 the sweater, and

(C) pulling the thus gripped waist portion axially of the sweater away from said shoulder portion while simultaneously subjecting the sweater to a charge of steam and subsequently to a charge of drying air.

20. A sweater finishing machine for processing sweaters

having a tight fitting ribbed waist portion, comprising: a base, a hollow vertically extending central column mounted on said base and extending upwardly therefrom, said central column being perforated throughout a substantial portion of its length, a finishing frame mounted on an upper portion of the central column for supportingly receiving a sweater to be finished, means for supplying processing fluids into the hollow interior of said central column, and baffle means mounted on said central column for receiving the ribbed waist portion of the sweater to be finished and controlling-by-limiting the flow of processing fluids through the ribbed waist portion.
